UNITED STATES PATENT OFFICE

94,874

DESIGN FOR AN ALPHABET FOR FORMING MONOGRAMS OR THE LIKE

Michael Chernow, Brooklyn, N. Y.

Application November 17, 1934, Serial No. 54,063

Term of patent 7 years

To all whom it may concern:

Be it known that I, Michael Chernow, a citizen of the United States and residing at Brooklyn, in the county of Kings and State of New York, have invented a new, original, and ornamental Design for an Alphabet for Forming Monograms or the like, of which the following is a specification, reference being had to the accompanying drawing, forming part hereof, and in which

Fig. 1 is a face view of the alphabet showing my new design.

Fig. 2 is a perspective view showing one of the letters of the alphabet.

Each of the characters of the alphabet com-

prises a solid block having a substantially flat back, said block being thin at two opposite edges thereof, said block having a convex face and being of substantially maximum thickness midway between said edges, the edge or edges of said character, other than said two thin edges, being of generally circular segmental conformation in end view.

I claim:

The ornamental design for an alphabet for forming monograms or the like, substantially as shown and described.

MICHAEL CHERNOW.
